UNITED STATES PATENT OFFICE.

MATTHEW F. CONNETT, JR., OF DAVENPORT, IOWA, ASSIGNOR TO LEWIS J. BROWN, NATHAN W. WARREN, PORTER H. BLANCHARD, AND THEODORE W. HARFORD, ALL OF SAME PLACE.

HAND FENCE-MACHINE.

SPECIFICATION forming part of Letters Patent No. 448,410, dated March 17, 1891.

Application filed January 5, 1891. Serial No. 376,785. (No model.)

To all whom it may concern:

Be it known that I, MATTHEW F. CONNETT, Jr., a citizen of the United States, residing at Davenport, in the county of Scott and State 5 of Iowa, have invented a new and useful Improvement in Hand Fence-Machines, of which the following is a specification.

My invention relates to improvements in hand wire-fence-making machines of the class 10 in which revolving twisting devices mounted upon guide-rings are employed for twisting wires in pairs together and over pickets which are placed at intervals between the wires while the twisting operation is being performed, the 15 pickets and lines of intertwined wires which hold the pickets in place affording the fence.

My object is to provide such a hand fence-machine of an improved construction which shall render it more simple, durable, and economical to manufacture than machines of the same class hitherto in use; and my object is, further, to provide a machine of this class adapted for use in twisting together wires which are provided with barbs.

25 In the drawings, Figure 1 is a broken view illustrating the upper portion of a fence in course of construction and showing one of my improved devices in operation thereon; Fig. 2, a section taken on line 2 2 of Fig. 1, viewed 30 in the direction of the arrow and enlarged; Figs. 3 and 4, enlarged views in elevation and partly sectional of parts of the revolving-twister detail, and Fig. 5 a broken enlarged end view of the same detail.

35 A is a guide-frame in the form of a ring, strengthened around its outer circumference by a rib *t*, which projects from between the two guide-surfaces *s* *s'*. The inner periphery of the ring affords a smooth annular 40 surface *r*. On one side the ring is provided with lugs *q* *q'*, through the medium of which the ring is secured at a tangent upon a bar *B*.

45 *C* is the revolving twister, which is made in two separable parts *C'* and *C''*. The part *C'* is formed along its outer edge with a segmental laterally or inwardly projecting flange *o*, the inner surface of which is smooth and describes substantially the arc of the outer surfaces *s* *s'* of the ring. Near opposite ends and at a

distance from the flange *o* of a little more than 50 the thickness of the edge portions of the ring *A* are projections or bosses *o'*, which, with the flange *o*, afford between them grooves embracing loosely the edge of the ring at one side. On the inner face of the part *C'* are sockets 55 *n*, and between the said sockets are two elongated openings *m*, the sockets and openings being in the relative positions shown. The part *C''* has a segmental inwardly-projecting flange *l*, coinciding in outline with the 60 rim *o*, two elongated openings *k*, coinciding in size and position with the openings *m*, and projections or bosses *k'*, coinciding with the bosses *o'* on the part *C'*. Upon the face of the part *C''* are lugs *i* *i'*, which at their free ends 65 extend into the sockets *n* *n'* of the part *C'*, and a lug *i'*, which extends against the inner face of the part *C'*, the lugs operating to maintain the parts the proper distance from each other, in which position they are securely held by a nut-bolt *h*. When adjusted 70 upon the ring *A*, the inner faces of the flanges *o* and *k* overlap the edge portions of the surfaces *s* *s'*, respectively, of the ring, and the bosses *k'* *o'* the edge portions of the inner 75 face *r* in a manner to permit the twister to travel freely around the ring.

In operation the wires *y* to be twisted, if plain—that is to say, unprovided with barbs—are passed, respectively, through the 80 respective openings *m* *k* and secured to a post. At, say, the next post the wires are inserted into a tension device, which may be the device *D*. (Shown in Fig. 1.) It comprises a bar *f*, provided along one end portion with 85 a series of headed studs *f'*, equidistant apart, and at its opposite end with a stud *f''*, upon which is a rotary drum *f''*, having end flanges formed with notches, there being a pawl *f''* upon the bar to enter and engage the notches 90 of one of the flanges to prevent negative rotation of the drum. Secured to the drum is a rope *f''*. The wires *y* are inserted into the tension device by passing them back and forth between the studs *f'*, as shown, and the 95 rope *f''*, secured to the post. With a suitable wrench the drum is then turned to wind the rope upon the drum *f''* until the wires are

sufficiently taut. The operator, grasping the bar B, gives to it and the ring A, bodily, a circular motion in a vertical plane, whereby the twister, being held to the center of the circle thus described by the wires y, passing through it, as described, revolves around the guide-ring in one direction, twisting the said wires with each revolution. The pickets x are placed between the wires at stated intervals, as shown, and as the wires are shortened by the twisting operation they pay out through the tension device D. In practice two or three rings A and twistlers would be mounted one above the other upon a single bar B and an equal number of tension devices provided, so that two or more sets of wires to form a complete fence may be twisted simultaneously.

In order that the twister may be employed where one or both of the wires y to be twisted carry barbs, I provide the twister at one or both ends with openings surrounded by hollow conic frustums e', affording bell-mouthed passages through which the barbed wire may pass without impediment. I prefer to provide the twister C with two such passages at opposite ends, and each passage with two bell-mouths extending in opposite directions, so that the device may be employed to travel in either direction along the barbed wires with equal readiness. In the construction shown each pair of oppositely-extending frustums is formed in one piece with the part C' of the twister, and for convenience in operation the point of junction between the frustums is at about the plane of the center of the twister.

In constructing a fence with my improved device of barbed wire it is preferable to provide the wire or wires with barbs after the wire has been strung between the initial post and tension device, so that in the twisting

operation the wire may pay out through the tension device.

Projecting laterally and outward from the rim portion of the part C² is a lip d, which is useful in pressing or hammering the pickets forward after they have been placed in position and before the twisting operation is resumed.

The construction described is subject to slight modifications in the matter of details which would not depart from the spirit of my invention.

What I claim as new, and desire to secure by Letters Patent, is—

1. In a fence-machine, the combination, with the guide-ring A, having the supporting-lugs q, of a twister C, in two parts bolted together, mounted to travel on the guide-ring, and having inwardly-projecting segmental rims overlapping the edges of the outer surface of the guide-ring and projections on their inner faces overlapping the edges of the inner surface of the guide-ring, lugs upon one of the said parts extending against the other part, and one or more passages through the twister for the wire to be twisted, substantially as and for the purpose set forth.

2. In combination, the guide-ring A, operating-bar B, tension device D, and a twister C, comprising two parts C' and C², embracing the edges of the guide-ring and held in fixed relation with each other by intervening lugs and a bolt h, one or more bell-mouthed passages through the twister for the wire to be twisted, and a laterally-projecting lip d on the rim of the part C², substantially as and for the purpose set forth.

MATTHEW F. CONNETT, JR.

In presence of—

J. W. DYRENFORTH,
W. J. FROST.
